UNITED STATES PATENT OFFICE.

ANGELO ROSSI, OF SANTA ROSA, CALIFORNIA.

VALVE-OPERATING STRUCTURE FOR MOTOR CYCLES.

Application filed September 8, 1925. Serial No. 55,183.

This invention relates to improvements in motorcycle construction and particularly to the valve tappet actuating means. In motorcycles of at least one certain standard 5 make, the rollers of the tappet actuating rocker arms operate on a single cam. This arrangement makes it impossible to give each tappet the proper dwell and raise of opening it should have, since conditions 10 which are correct for the intake valve are not suitable for the exhaust valve and vice versa.

The results are that the engine cannot function to the best of its ability and only 15 mediocre efficiency is obtained.

The principal object of my invention therefore is to eliminate the above defects in operation by arranging an individual cam for each rocker arm, so that the cams can be 20 designed to give such lift and dwell to the tappets as has been determined to be most suited for the purpose by the best engineering practice.

At the same time the structure is such 25 that no changes have to be made to the standard engine assembly in order to install my structure therein.

A further object of the invention is to produce a simple and inexpensive device 30 and yet one which will be exceedingly effective for the purpose for which it is designed.

These objects I accomplish by means of such structure and relative arrangement of parts as will fully appear by a perusal of 35 the following specification and claims.

In the drawings similar characters of reference indicate corresponding parts in the several views:

Fig. 1 is a fragmentary end outline of the 40 gear box of a motorcycle and certain of the gearing therein, showing my tappet operating mechanism as arranged for one cylinder.

Fig. 2 is a side view of the cam, gear and rocker arm unit detached.

Fig. 3 is an end view of the same.

Referring now more particularly to the characters of reference marked thereon, the numeral 1 denotes the gear case of the motorcycle in which as standard equipment are 50 mounted a pinion 2 on the crankshaft 3, said pinion driving a gear 4 which in turn drives a gear 5 the same size as said gear 4.

The gears 4 and 5 which I retain are used in connection with the valve operating 55 mechanism of the two cylinders of the motorcycle, if the engine is of course a two

cylinder engine. Since such mechanisms are identical I only show and describe one of the same.

Such mechanism for the valves of each 60 cylinder comprises a pair of cams 6 and 7 for the intake and exhaust valves respectively, which cams are permanently connected to a gear 5 so as to turn as a unit on the gear shaft 8. These cams are set at such positions relative to each other that the opening of the different valves will be properly timed with respect to each other, and they are so designed that the valves will have the proper amount and dwell of lift. 70

Independently turnable on a stub shaft 9 mounted in the case 1 above the gear 5 are oppositely disposed rocker arms 10 and 11 for the cams 6 and 7 respectively.

The lower ends of the rocker arms carry 75 rollers 12 and are offset from each other transversely so that said rollers will bear on the respective cam faces without interference. The opposite upper ends of the rocker arms have pads 13 disposed in longitudinal 80 alignment to align with the lower ends of the corresponding valve tappets 14 which project into the case 1. In installing my improved structure it is only necessary to remove the original gears 4 and 5 and their 85 cams, together with the rocker arms, and replace such parts with the corresponding members constructed according to my invention.

As previously stated, these improved parts 90 fit in place in the gear case without necessitating any changes being made to the case or to any other members of the engine assembly.

From the foregoing description it will be 95 readily seen that I have produced such a device as substantially fulfills the objects of the invention as set forth herein.

While this specification sets forth in detail the present and preferred construction of 100 the device, still in practice such deviations from such detail may be resorted to as do not form a departure from the spirit of the invention, as defined by the appended claims.

Having thus described my invention what 105 I claim as new and useful and desire to secure by Letters Patent is:

1. An operating structure for an adjacent pair of transversely aligned motorcycle valve-tappets, comprising a pair of opposed rocker arms pivoted independently of each other, the upper and opposite ends of said arms 110

being in common transverse alinement to bear against the tappets, rollers projecting from the same side of the arms at their lower opposed ends and arranged so as to be laterally offset, and independent cams to engage the rollers mounted on a common axis, said cams being of different diameters and the larger cam being the farthest from the plane of the arms whereby to enable the rollers being of the same size while preventing the apex of one cam from striking the arm of the other roller at any period in its rotation.

2. An operating structure for an adjacent pair of transversely alined motorcycle valve-

tappets, comprising a pair of opposed rocker arms pivoted independently of each other, the upper and opposite ends of said arms being in common transverse alinement to bear against the tappets, rollers projecting from the same side of the arms at their lower opposed ends and arranged so as to be laterally offset, and independent cams to engage the rollers mounted on a common axis, the distance from the axis of the cams to the lower end of one arm being not less than the greatest radius of the cam of the other arm. 20 25

In testimony whereof I affix my signature.
ANGELO ROSSI.
